[57] ABSTRACT

A heating apparatus using liquid fuel, of the kind comprising a frame, a source of fuel such as a reservoir, a pump or a fuel intake, and a combustion chamber supplied with fuel through the intermediary of a constant-level tank, in which the source and the tank conjointly form a supply unit removably mounted in the frame, separable coupling means being provided between the supply unit and at least one pipe mounted on the said frame. The modified apparatus lends itself very rapidly to a standard replacement.

HEATING APPARATUS USING LIQUID FUEL

The present invention relates to heating apparatus using liquid fuel, commonly known as fuel-oil heaters.

Such heating apparatus generally comprise a fuel reservoir supplying a combustion chamber through the intermediary of a constant-level tank. The constant-level tank limits the delivery flow-rate of fuel to the combustion chamber which is equipped with a burner which is most frequently a gasification type burner.

Heating apparatus of this type gives satisfaction for the most part, but it is sometimes subject to operational defects which affect its heat efficiency and even result in breakdown.

Experience has shown that the majority of these incidents of operation or breakdowns are due to the presence of foreign substances which contaminate the fuel employed. These substances are most frequently water, sludges or other such impurities.

These impurities are gradually deposited in the reservoir, and when they reach a certain level, they are carried away into the constant-level tank, the flow-regulation capacity of the constant-level tank is thereby disrupted.

Services of a specialist then become necessary.

Such specialists frequently encounter numerous difficulties in obtaining access to the reservoir and to the constant-level tank, which are generally fixed rigidly to the frame of the heating apparatus and are protected by a casing fixed to this frame.

These difficulties are increased if it becomes further necessary to completely clean the fuel supply systems.

In particular, if it is necessary to drain the reservoir so as to eliminate completely the water therefrom, the whole of the heating apparatus must be sent back to the factory for putting into order, since such an operation cannot be conveniently carried out on site, where the heating apparatus is installed.

Furthermore, in most favorable circumstances, this operation necessitates several hours' work.

An aim of the present invention is a heating apparatus using liquid fuel, which is free of such disadvantages.

The heating apparatus utilizing liquid fuel according to the invention is of the kind comprising a frame, a combustion chamber fixedly mounted on the frame, a pipe mounted on the frame for supplying the combustion chamber with liquid fuel, a fuel supply unit removably mounted on the said frame and comprising a fuel reservoir and a constant-level tank, and coupling means for detachably interconnecting said unit and said pipe, said coupling means comprising a first complementary connecting portion fixedly mounted relative to and in communication with the constant-level tank and a second complementary connecting portion fixedly mounted on the frame in communication with the pipe, said coupling means being so positioned as automatically to bring the fuel supply unit into operative connection with the pipe when the said unit is placed in position on the frame.

Thus, in the case of any operating difficulty, it is simply necessary to remove the supply unit for an examination and, if necessary put it back in working order.

If necessary, it is also possible to effect a standard replacement of this supply unit.

The replacement does not necessitate any special tools and may be carried out very rapidly, with sufficient rapidity to avoid the stopping of the heating apparatus.

If the supply unit once removed from this heating apparatus cannot be put into working order on site, it is sent back to the factory for checking, cleaning and adjustment, while the heating apparatus continues to work with the new supply unit, clean and correctly regulated.

The trouble caused to a user by this action is therefore a minimum.

The characteristic features and advantages of the invention will further be brought out in the description which follows below, given by way of example, reference being made to the accompanying diagrammatic drawings, in which:

FIG. 1 is a view in elevation, with parts broken away, of a heating apparatus according to the invention, in working order;

FIG. 2 is a view similar to FIG. 1 during the course of the replacement with a standard supply unit for this heating apparatus;

FIG. 3 is a partial view in perspective of this supply unit;

FIG. 4 is a partial view in cross-section of the heating apparatus according to the invention, taken along the line IV-IV of FIG. 2;

FIG. 5 is a partial view in elevation showing a detail of FIG. 1 to a larger scale and with parts broken away.

In the embodiment chosen and illustrated in these drawings, a heating apparatus comprising a frame 10 forms a parallelepiped structure. On this frame 10 is fixed laterally a casing 11 and an access grating 12 is hinged at the upper part of frame 10.

A known heating apparatus of this kind comprises, in the frame 10, a liquid fuel reservoir 13, a constant-level tank 15 coupled to the reservoir 13 by a pipe 16, and a combustion chamber 17 supplied with fuel by the constant-level tank 15 through the intermediary of a pipe 18.

In the present apparatus, the reservoir 13 and the constant-level tank 15 are fixed on a support plate 19 and form therewith a supply unit 20 removably mounted on the frame 10.

The frame 10 is therefore provided for that purpose with two rigidly fixed slides 21 which extend along the height of the heating apparatus, parallel to the combustion chamber 17, and are held at a distance from the combustion chamber 17 by cross-members 22, of which only one is shown in the drawings. A free ventilation zone 23 is thus formed between these slides 21 and the combustion chamber 17.

The slides 21 are connected together by a partition 25 on their side nearest the combustion chamber 17.

The support plate 19 of the supply unit 20 also forms a partition and is provided with lateral flanges 26 adapted to cooperate with the slides 21. The support plate 19 can thus be fitted into the volume delimited by the slides 21, as indicated in chain-dotted lines in FIG. 4. When in position in the slides 21, the plate 19 in combination with the partition 25 which joins the slides together forms a double wall and rests on an abutment 27 carried by the partition 25.

At the upper end of the support plate 19 an opening 28 is provided which forms a lifting handle.

The reservoir 13 is fixed to the support plate 19 by means of brackets 29 which hold it at a distance from the plate 19. Similarly, the constant-level tank 15 is fixed on the plate 19 by means of a bracket 30 which holds it at a distance from the plate 19, and to which it is fixed by legs 31.

It is not necessary to go into any detail in respect of such a constant-level tank. It is simply necessary to say that it is provided internally with a float 32 which maintains a constant level 33 in the tank by acting for that purpose on the discharge of the conduit 16 into the said tank.

The tank 15 is further provided with a coupling sleeve 35 passing through the bottom thereof and which is capable of being supplied with fuel under the control of a valve member 36. The member 36 is operated by a rod 37 coupled to an actuating knob 38 disposed at the top of the reservoir 13.

The frame 10 carries a fixed nozzle 40 which is connected to the supply pipe 18 for the combustion chamber 17 and is complementary to the coupling sleeve 35 of the tank 15. This nozzle 40 is arranged vertically below the coupling sleeve 35.

It is therefore merely necessary to position the tank 15 on the nozzle 40 to ensure the communication of this tank with the combustion chamber 17, the fluid-tightness of this assembly being ensured by annular or toroid seats 42 which, in the present example are carried by the nozzle 40.

In the event of a fault in operation of the heating device, it is simply necessary to close the valve member 36 by actuating the operating knob 38, to removing the supply unit 20, and if necessary, installing in its place a new supply unit by the engagement of the coupling sleeve 33 of the tank 15 of the new unit on the fixed nozzle 40 carried by the frame 10 and the supporting of this unit on the abutment 27.

This new supply unit is from that time ready to be put into operation by actuation of its control knob 38.

The standard supply unit replacement thus effected can be carried out fairly rapidly so that the combustion chamber 17 remains supplied by the volume of fuel contained only in the pipe 18.

In case such a standard replacement is not essential, especially where the defective supply unit can easily be put into working order on site, it will be appreciated that its removal from the frame 10 facilitates its examination and repair, and that this removal and the subsequent replacement in position are effected very quickly.

It will also be appreciated that in service the reservoir 13 and the constant-level tank 15 of the supply unit are separated from the combustion chamber 17, successively by a first ventilation space between this reservoir and the tank on the one hand and the supporting plate 19 on the other, a second ventilation spaced formed between the double wall formed by the plate 19 and the partition 25 which couples together the slides 21, and finally the ventilation space 23 arranged between this partition 25 and the combustion chamber 17.

The present invention is not limited to the form of embodiment described and shown, but includes any alternative form of construction.

In particular, the separable coupling means provided between the tank 15 and the pipe 18, comprising a

sleeve 35 carried by the tank 15 and a fixed nozzle 40 carried by the frame and coupled to the pipe 18, may be replaced by any other appropriate separable coupling means, in particular a nozzle carried by the tank and a fixed complementary sleeve carried by the frame and connected to the pipe 18.

In the example of construction described above, the supply unit comprises an individual reservoir which serves as a fuel source.

The reservoir may be replaced by a pump coupled to an external fuel reservoir intake. This may be the case in certain installations in which various individual heating apparatus are supplied by a common reservoir.

In the case for example in which the reservoir 13 is replaced by a pump, separable coupling means of the same type as those described above for the constant-level tank are provided in addition between this pump and a pipe fixed to the frame and connected to the external fuel reservoir.

What I claim is:

1. A heating apparatus using liquid fuel comprising a frame, a combustion chamber fixedly mounted on the frame, a pipe mounted on the frame for supplying the combustion chamber with liquid fuel, a fuel supply unit removably mounted on the said frame and comprising a fuel reservoir and a constant-level tank, and coupling means for detachably interconnecting said unit and said pipe, said coupling means comprising a first complementary connecting portion fixedly mounted relative to and in communication with the constant-level tank and a second complementary connecting portion fixedly mounted on the frame in communication with the pipe, said coupling means being so positioned as automatically to bring the fuel supply unit into operative connection with the pipe when the said unit is placed in position on the frame, said first complementary connecting portion of said coupling means comprising a

25 coupling sleeve and the second complementary connecting portion comprising a fixed nozzle, the coupling sleeve being adapted to be fitted directly on the nozzle.

2. A heating apparatus according to claim 1, wherein the nozzle-sleeve combination has a fluidtight seal.

3. A heating apparatus according to claim 2, wherein said supply unit further comprises a support plate on which said reservoir and said tank are fixed, said support plate being slidably mounted in slides rigidly fixed on said frame.

4. A heating apparatus according to claim 3, wherein the slides are spaced from the combustion chamber so that a ventilation space is formed between said combustion chamber and said supply unit.

5. A heating apparatus according to claim 3, wherein the support plate forms a partition having lateral edges cooperating with the slides, and wherein said slides are connected to each other by a partition along their sides remote from the supply unit, so that the combustion chamber is separated from the supply unit by a double wall when the supply unit is in position on the frame.

6. A heating apparatus according to claim 3, wherein said reservoir and said tank are fixed to the support plate of said supply unit by brackets which hold them at a distance from the said plate.

7. A heating apparatus according to claim 1, wherein said supply unit has a lifting handle.

8. A heating apparatus in accordance with claim 3,
wherein said supply unit has a lifting handle comprising
an opening formed in said support plate.
